UNITED STATES PATENT OFFICE

MILES F. YOUNT, OF BEAUMONT, TEXAS

SHEAVE

Application filed May 16, 1929. Serial No. 363,696.

My invention relates, broadly speaking, to improvements in sheaves, but has particular reference to the sheave type line guide for draw works as disclosed in my Patent No. 5,157,016, dated January 19, 1926.

An outstanding object of this invention is to provide in a sheave type line guide means for effectively lubricating the line passing through the guide and at the same time lubricating the bars upon which the sheaves are slidably and rotatably mounted.

A further object resides in the provision of a novel sectional sheave having means for efficiently and economically supplying lubricant to both the axis and periphery, and this without weakening the construction or otherwise effecting loss of efficiency.

Another object of the invention is to furnish a sectional sheave incorporating a lubricant chamber intermediate the axis and periphery and including novel wick means for conveying lubricant to both the axis and periphery.

The invention also resides in certain novel features of construction, combination and arrangement of the various parts and in certain modes of operation,—all of which will be readily understood and appreciated by those skilled in the art upon reference to the accompanying drawings in connection with the following detailed description.

The drawings illustrate the now preferred embodiment of the invention,—the same, however, being capable of other mechanical expressions within the spirit and scope of the subject matter claimed hereinafter.

In the drawings,

Figure 1 is a side elevational view partly broken and illustrating a sheave incorporating my invention;

Figure 2 is an edge elevation of the device;

Figure 3 is a sectional view taken on the line 3—3 of Figure 1;

Figure 4 is a sectional view taken on the line 4—4 of Figure 1;

Figure 5 is a fragmentary perspective view of one of the sections of the sheave;

Figure 6 is a perspective of a line guide

and illustrating the application of my invention therein, and

Figure 7 is a fragmentary perspective of the wick.

Referring specifically to the drawings wherein the same reference characters illustrate the same parts in all views, letter A designates the head board of a draw works incorporating a winding drum B for the cable C, which passes between the sheaves 5, 5, which are slidably and rotatably mounted on shafts 7, 7. One of the shafts 7 is arranged above and in advance of the other. Both shafts are adjustably carried by brackets D secured to the head board A. In the winding of the cable C upon the drum B it will be obvious that the sheaves move axially of their shafts, the cable C passing between the sheaves downwardly, as shown. Since the sheaves partake of longitudinal sliding movement in addition to their rotation it will be obvious that considerable lubricant will be required. Furthermore, the passage of the steel cable or line between the guide sheaves effects considerable wear upon both sheaves and the line or cable.

As previously intimated, the present invention has for one of its objects to provide for the lubrication of the periphery of the sheaves and also of the shafts 7 upon which the sheaves rotate and slide. Thus, wear on the cable and sheaves will be reduced and easier rotation and sliding of the sheaves on the shafts effected.

The general arrangement hereinabove referred to is depicted in Figure 6.

In carrying out the invention each sheave is made in duplicate sections 5, each of which has an outward hub portion 6 for the bearing shaft 7,—the sections being tied together by two series of bolts 8, 9, respectively, which are radially spaced, as shown.

The periphery of each section 5 is beveled inwardly, as at 5a, toward its inner face to provide the cable receiving groove 10,—it being also noted that the sheave is provided with an annular lubricant chamber formed by opposed circumferential grooves 11 in the inner face of each section. A substantially disc-like wick 12 is interposed between the

sections 5 extending, as shown, through the annular lubricant chamber 11, 11.

The outer periphery of the wick 12 extends to a point flush with the bottom of the line groove 10 and in fact forms the intermediate bottom portion thereof, so that the line in said groove will come into direct stressing contact with the wick 12.

Lubricant is supplied to the annular chamber formed by opposed circumferential grooves 11,—there being provided, as shown, a boss 13 extending from the side of one of the sections 5, this boss having a duct 13a communicating through the section 5, as shown. The outer end of the duct 13a is adapted to be closed by a cover or closure 14.

Particular attention is directed to the bosses 8b, 9b, protruding from the inner face of each section and through which the respective bolts 8, 9 extend. The bosses 8b serve to tightly compress the wick 12 at circumferentially spaced points adjacent the periphery of the sheave, while the adjacent or surrounding base portion of such bosses 8b serve to compress the wick also, but of course to a lesser degree. The base portions of the bosses 8b are designated as 8c. The effect of the bosses 8b, 8c is, therefore, to compress the wick at circumferentially spaced points adjacent the periphery of the sheaves and also to crowd the wick laterally intermediate such bosses so that the same will maintain contact with the opposed surfaces of the section 5 between the bosses 8b, 8c. The bosses 8b, 8c therefore tend to facilitate the economical supply of lubricant to the line groove 10 of the sheaves and serve as a check upon the capillary action of the wick 12 at points therebetween.

The inner series of bosses 9b surrounding the hub 6 at the inner faces of the sections 5 are adapted to be brought into bearing contact by the bolts extending therethrough, thus, providing a very rigid assembly of the sections 5 at the site of the hub 6, 6. The surrounding ledges or base portions 9c of the bosses 9b, serve to compress the wick after the fashion of the ledges or base portions 8c mentioned in connection with the bosses 8b. It is to be understood that the wick 12 will be cut out to provide recesses 12a for the reception of bosses 9b,—the ledge or base portions 9c bearing against the surface of the wick immediately adjacent each boss 9b in attempting to crowd the portions of the wick laterally at such points for contact with the surface of the sections between ledges 9c.

Figure 5 clearly shows that between the ledges 9c there is in effect provided passages 9d for the passage of lubricant to the shafts 7 whereby the same will be effectively lubricated at all times, but without however allowing a waste of the lubricant,—which is to say an excessive supply thereof to shafts 7.

By the simple oiling and line guide sheave as applied to the hoisting line of a draw works per Figure 6 it will be apparent that all other sheaves and pulleys coming in contact with line C will be oiled and thus kept in a satisfactory workable condition at all times without manual attention.

Having thus described my invention, what I claim as new and desire to secure by Letters Patent is:

1. A guide sheave comprising beveled circular plates and opposed annular grooves providing an oil chamber and the beveled portions of the plates forming a line guide when the plates are assembled together, and having hubs for the passage of a shaft, inwardly projecting bosses extending from said plates outwardly of said oil chamber, a second series of bosses extending inwardly from said plates adjacent the hub portions thereof and adapted to be brought in flat contact with one another, bolts extending through said last mentioned bosses for fastening the plates together, there being spaces between opposed ones of each set of bosses, the first mentioned set of bosses being spaced from one another when the second mentioned set of bosses are contiguous, a disc-like wick member interposed between said plates and having recesses adapted to receive said second mentioned bosses, said wick extending to the shaft, bolts extending through said first mentioned bosses to compress said wick at spaced peripheral points.

2. The combination set forth in claim 1, and means for supplying lubricant to said oil chamber.

3. A guide sheave or the like comprising substantially duplicate disc members, each including a hub portion having a bearing for the passage of a shaft, bosses extending inwardly from said plates adjacent said hub portion, bolts extending through said bosses for binding opposed ones thereof into flat contact, there being spaces between said bosses communicating with said bearing, inwardly extending opposed bosses arranged at spaced peripheral points adjacent the periphery of said disks, a wick member interposed between said plates, and one of said plates having a circumferential inner surface groove communicating with said wick and providing an oil chamber, said wick establishing lubricating communication with the periphery of said sheave and the axis thereof.

4. A guide sheave or the like comprising substantially duplicate disc members, each including a hub portion having a bearing for the passage of a shaft, bosses extending inwardly from said plates adjacent said hub portion, bolts extending through said bosses for binding opposed ones thereof into flat contact, there being spaces between said bosses communicating with said bearing, a wick mem-

ber interposed between said plates, and one of said plates having a circumferential inner surface groove communicating with said wick and providing an oil chamber, said wick 5 establishing lubricating communication with the periphery of said sheave and the axis thereof, and inwardly extending opposed bosses arranged in series adjacent the peripheries of said discs outwardly of said oil chamber for compressing said wick at spaced peripheral points.

5. A guide sheave comprising beveled circular plates having hubs for the passage of a shaft, bosses extending inwardly from said plates adjacent said hub portion, bolts extending through said bosses for binding opposed ones thereof into flat contact, there being spaces between said bosses communicating with said shaft, a wick member interposed between said plates, one of said plates having a circumferential inner surface groove communicating with said wick and providing an oil chamber, said wick establishing lubricating communication with the periphery of 20 said sheave and the axis thereof, and inwardly extending opposed bosses adjacent the peripheries of said plates outwardly of said oil chamber for compressing said wick, and fastening means extending through said last 25 named bosses.

6. A guide sheave comprising beveled circular plates having hubs for the passage of a shaft, bosses extending inwardly from said plates adjacent said hubs, bolts extending 30 through said bosses for binding opposed ones thereof into flat contact, there being spaces between said bosses communicating with said shaft, a wick member interposed between said plates, and one of said plates having a circumferential inner surface groove communicating with said wick and providing an oil 35 chamber, said wick establishing lubricating communication with the periphery of said sheave and the shaft, and inwardly extending opposed bosses adjacent the peripheries of said discs outwardly of said oil chamber for compressing said wick, and fastening means extending through said last named bosses said bosses having base portions of reduced 40 thickness adapted for pressure contact with said wick.

7. A guide sheave comprising substantially duplicate disc members, each including a hub portion having a bearing for the passage of a shaft, bosses extending inwardly from said plates adjacent said hub portion, bolts extending through said bosses for binding opposed ones thereof into contact, inwardly extending opposed bosses arranged 45 at spaced peripheral points adjacent the periphery of said disks, a wick member interposed between said plates, said wick member being compressed at spaced peripheral points between said latter bosses.

65 8. A guide sheave comprising substantially

duplicate disc members, each including a hub portion having a bearing for the passage of a shaft, bosses extending inwardly from said plates adjacent said hub portion, bolts extending through said bosses for binding opposed ones thereof into contact, inwardly extending opposed bosses arranged at spaced peripheral points adjacent the periphery of said disks, said latter bosses having steps, a wick member interposed between said plates, said wick member being compressed at spaced peripheral points between said latter bosses, said bosses giving different compressions to said wick at the stepped portions thereof.

In testimony whereof I affix my signature.
